UNITED STATES PATENT OFFICE.

CARL L. HERTEL, OF COLUMBUS, INDIANA, ASSIGNOR TO CARL L. HERTEL AND EDWARD KITZINGER, OF COLUMBUS, INDIANA, A COPARTNERSHIP.

D-HANDLE.

Application filed July 16, 1926. Serial No. 122,766.

My invention relates to an improvement in D-handles.

It has heretofore been proposed to make a D-handle out of two mating stampings, 5 which, at one end were each provided with a grip receiving socket and at the other end with a half stale-receiving socket but difficulty has been heretofore experienced in holding the two stampings together under 10 the stresses to which the structure is subjected when the tool is being used.

My improvement is of such character that the two mating stampings may be readily assembled within my improved retaining 15 thimble, the tapered end of the stale serving to firmly hold the parts in assembled condition.

The accompanying drawings illustrate my invention. Fig. 1, is a side elevation of my 20 improved handle in partial section, Fig. 2, a perspective view of one of the handle stampings, Fig. 3. a perspective view of the thimble.

In the drawings 10 indicates the mating 25 handle stampings or handle section formed most conveniently of metal stampings each having a grip receiving socket 11 at one end and a stale-receiving half-socket 12 at the other end.

30 My improved thimble comprises a tubular conical main portion 13, adapted to receive and retain the half sockets 12 of members 10 and the end strap or bridle 14 adapted to over-lap the junction of the two elements 10 the thimble being cut away at 15, 15 at each 35 side of the strap 14 in such manner as to permit insertion therethrough of the half sockets 12.

The adjacent edges 16 of the half sockets 40 12 are slightly flared from each other to facilitate assembly of the parts.

It will, of course, be readily understood 45 that the handle elements 10, 10 need not be hollow stampings but may be of any other desired form so long as they provide the half stale-sockets 12.

The parts are assembled by projecting the two handle elements 10 through the openings 15 and then driving the slightly tapered end of the stale into the socket formed 50 by the two half sockets 12 thus forcing the elements 10 into close engagement with the strap 14 and spreading the half sockets 12 firmly into the tapered main body 13 of the thimble; whereupon the parts may be firmly 55 held in place by means of rivets 17 passed through the thimble, the half sockets and the stale.

The parts may be further secured together, if desired, by passing a bolt 18 60 through the outer end of element 10 and the grip 19.

I claim as my invention:—

1. A D-handle comprising a pair of mating handle elements each having a half stale 65 socket at one end, and an embracing thimble for said half sockets, said thimble having openings at each side at one end through which the stale receiving half sockets of the handle elements may be projected into the 70 thimble, and an adjacent portion over-lapping the handle elements diametrically of the thimble.

2. A D-handle comprising a pair of mating handle elements each having a half stale-socket at one end and a thimble comprising 75 a sleeve portion adapted to sleeve over the stale-sockets and a bridle portion carried at one end of the sleeve portion, said bridle portion being spaced from the sleeve portion 80 so that the stale sockets may be projected into the sleeve portion and the bridle portion will overlie the adjacent portions of the handle elements, substantially as shown 85 and described.

In witness whereof, I have hereunto set my hand at Indianapolis, Indiana, this 13th day of July, A. D. one thousand nine hundred and twenty six.

CARL L. HERTEL.
